UNITED STATES PATENT OFFICE.

OTIS K. RICHARD AND CLEMENT C. RICHARD, OF DETROIT, MICHIGAN.

WHEEL-ANCHORING DEVICE.

Application filed November 21, 1921. Serial No. 516,534.

This invention relates to wheel anchoring devices and the object of the invention is to provide a wheel anchoring device for securing automobiles for shipment to prevent movement thereof. This invention is particularly drawn to a wheel anchoring device of the character described which is formed from round edge strip stock of about 16 gauge, though a heavier or lighter stock 5 may be used. There have been several attempts to make a wheel anchoring device of this type heretofore but the greatest difficulty encountered has been to bend the strip stock so that no sharp edges are provided which 10 might cut into the wheel spokes or felloe. The object of this invention, is therefore, to provide a wheel anchoring device made of strip stock so formed as to eliminate sharp or angular edges which would mar the finish 15 of the wheel with which it is used. Another object of the invention is to provide a method of forming a wheel anchoring device out of round-edge strip stock which may be obtained at a very low cost and which, when 20 completed, provides a device of much greater strength than those now in use. Another object of the invention is to provide a wheel anchoring device formed of round-edge strip stock of a uniform width throughout in 25 which a pair of lugs are struck up by means of which a cloth wrapping may be secured about the portion of the device fitting about the wheel spoke and felloe. These objects and the several novel features of the invention 30 are hereinafter more fully described and claimed and the preferred form of construction by which these objects are attained is shown in the accompanying drawings in which—

Fig. 1 is a plan view of the strip stock 40 after the first operation of offsetting a portion thereof.

Fig. 2 is a plan view of the same piece with the offset portion turned up at a right 45 angle, the feet form and the lugs struck up.

Fig. 3 is a side elevation thereof prior to bending about the spoke form.

Fig. 4 is an elevation of the device after being bent about the spoke form and showing the legs in dotted lines bent downwardly 50 to position.

Fig. 5 is a side elevation of the device showing the method of securing the nailing plate thereto.

Fig. 6 is a perspective view of the com-

pleted device and its position relative to the wheel.

Fig. 7 is a plan view of the nailing plate.

As shown in Fig. 1 the strip stock 1 is placed in a die with a number of similar pieces in which the central portion 2 thereof is offset so that the inner edge 3 of the portion 2 is in alignment with the edge 4 of the body 1. The device as shown in Fig. 1 is then placed in another die in which the portion 2 is turned up at a right angle to the body 1 in alignment with the said edge 4 and a pair of lugs 5 are struck up from the member 1 as shown in Figs. 2 and 3. At the same time the ends of the strip stock 60 are bent up to form a foot 6 at each end each foot having a portion 7 bent at a right angle to the portion 6 for a purpose hereinafter described. At this time the portion 2 is bent around a spoke form 8 shown in 70 dotted lines in Figs. 2, 3 and 4 so that the legs 1 extend horizontally from the portion 2 as shown in Fig. 4. It will be noted that the portion 2 at each end cannot bend due to the angular formation where the portions 80 1 are bent to form the portion 2 and due to this fact the bend in the portion 2 will be centrally between the ends 9 of the body portion 1 shown in Fig. 2. For this reason the feet 6 which are equi-distant from the center of the device will come to alignment when bent as shown in Fig. 4, and it will be noted that the portion 2 when bent as shown in Fig. 4 is bowed slightly so that the edges 90 extend away from the spoke. When the portion 2 has been bent as shown in Fig. 4 the legs 1 are bent downwardly as shown in dotted lines to provide a shoulder 10 which extends over the felloe of the wheel in use as shown in Fig. 6. The securing plate 11 shown more particularly in Fig. 7 is provided with a slot 12 which is passed over the upturned end 7 of the foot 6 as shown in Fig. 5, and is moved around so that the same lies flat on the foot 6, the central aperture 100 13 being positioned in alignment with an aperture 14 in the foot 6 as shown in Fig. 6. At this time the upturned end 7 shown in Fig. 5, is bent over to the dotted position to secure the plate 11 in place, the bent end 105 7 being shown in full in Fig. 6. The final operation is to pad the device to prevent the same from marring the wheel and this is accomplished as shown in Fig. 6 by wrapping the portion of the device between the lugs 110

5 with a strip of heavy cloth 15, the said cloth being wound back and forth until a thick pad is built up at which time the cloth pad is firmly secured in place on the device by clinching the lugs 5 over the ends thereof.

In use a pair of blocks are provided (not here shown) in which the tire engages and which prevent the wheel from rolling, as will be readily understood. The tire, shown in dotted lines in Fig. 6, engages the floor of the freight car between the said blocks and the wheel anchoring device is provided to hold the wheel down in the blocks and prevent it from riding over the same. When the wheel has been positioned in the blocks the wheel anchoring device is positioned around the spoke 16 and engages the felloe 17 of the wheel, as shown in Fig. 6, the pad 15 preventing the finish of the wheel from being marred. A series of nails 19 are then driven through the apertures 14 and 18 of the plates 11 and when this is done the legs 1 are slightly bowed, as shown in Fig. 6, which puts a spring tension on the device and holds the padded portion 15 in tight engagement with the spoke and felloe. By providing the apertures 13 and 14 at the base of the legs 1 through which nails may be driven, it is found that it takes over twice the pressure to pull up the plates 11 as when the plates are only nailed through the apertures 18 at the corners.

From the foregoing description it becomes evident that the device is very simple and efficient in operation, is easily and cheaply made, is of very strong construction and provides a device which accomplishes the objects described.

Having thus fully described our invention, its utility and mode of operation, what we claim and desire to secure by Letters Patent of the United States is—

1. A wheel anchoring device consisting of a flat strip of metal of uniform width throughout having an offset portion at the center bent up at a right angle to the plane of the strip, the said portion being further bent to a U shape and being adapted to engage about the spoke of a wheel, the legs of the said member being bent at an angle to the plane of the U shaped portion, and an apertured plate secured to the end of each leg.

2. A wheel anchoring device consisting of a flat strip of metal of uniform width throughout having an offset portion at the center bent up at a right angle to the plane of the strip, the said portion being further bent to form a U shape adapted to engage about the spoke of a wheel, the legs of the strip being bent at an angle to the plane of the U shaped portion, and an apertured plate secured to each end of the strip.

3. A wheel anchoring device comprising a flat strip of metal of uniform width having

an offset portion at the center bent up at a right angle to the plane of the strip, the said portion being further bent to form a U shape adapted to engage about the spoke of a wheel, the legs of the strip being bent at an angle to the plane of the U shaped portion, a lug struck up from each leg adjacent the U bend, a pad wound about the U shaped portion and being secured in place by the said lugs, and a foot provided at the end of each leg.

4. A wheel anchoring device formed of a flat strip of metal of uniform width, said device being formed by first offsetting a portion at the center a distance substantially equal to the width of the strip, the said offset portion being bent at a right angle to the plane of the strip and extending in practically parallel alignment with the edge of the strip toward which the central portion is offset, the said offset portion being then bent to a U shape and bowed across its width, the legs of the U shape being further bent at an angle to the plane occupied by the U bend, a lug struck up from each leg adjacent the U bend, a pad wound about the U bend and secured in place by the said lugs, and means at the ends for attaching the legs to a floor.

5. A wheel anchoring device comprising a flat strip of metal of uniform width throughout its length having a portion intermediate the ends offset approximately equal to the width of the strip, the said offset part being bent at a right angle to the plane of the strip and bent to form a U shaped member, the legs of the device being bent so that the central bent portion is positioned at an angle to the legs of the device and adapted to engage about the spoke of a wheel with the bends of the legs practically at the edge of the felloe of the wheel, the central U bent portion being further formed on a curve with the edges out of contact with the wheel spoke and the parts engaging the felloe also being similarly bent transversely whereby when the anchoring device is in position the edges of the strip are out of contact with the spoke and felloe, the terminal portions of the legs having apertured plates attached thereto providing feet for securing the anchoring device to the floor or structure on which the wheel rests.

6. A wheel anchoring device formed of a flat strip of metal of uniform width, said device being formed by first offsetting the portion at the center a distance substantially equal to the width of the strip, said offset portion being bent at a right angle to the plane of the strip, the point of the bend being on a line practically parallel with the edge of the strip toward which the central portion is offset, the said strip then being bent in U shape with the offset bent portion at the bend, the legs of the U shape being further bent at an angle to the plane oc-

cupied by the **U** bend, the metal about the **U** bend from about the point that the legs are bent being curved in cross section, the said legs being adapted at the ends for attachment to a floor and the legs extending at an angle to the wheel, the length of the legs being such that they are bowed in form and under tension when fastened.

7. A wheel anchoring device comprising a flat strip of metal of uniform width throughout its length having a portion intermediate its ends bent at an angle to the body of the strip and further bent to form a **U** shape, the legs further being bent adjacent the **U** bend whereby the said **U** bend extends at an angle to the legs providing a part to extend about the spoke and engage the felloe of a wheel substantially as shown, the said bent portion having a cloth or fabric material secured about the **U** bent portion, an anchoring plate for the terminal portion of each end of the strip, said plate having a series of apertures for fastening the device, and further having a slot through 25 which the end of the leg may be passed, said

leg extending through the slot and forward under the device and being return bent about the forward edge of the device, the said bent end of each leg having an aperture therein in registration with an aperture of the respective plate whereby at least one of the fastening nails or screws extends through both the plate and bent end of the leg.

8. A wheel anchoring device comprising a flat strip of metal of uniform width throughout its length bent at the center to provide a part at a right angle to the plane of the body and further bent in a **U** shape to engage about the spoke of a wheel, foot plates providing terminals for the legs and adapted for attachment to a floor surface, a padding means on the said **U** shaped part, and lugs struck up from the metal of the device providing fastening means for the padding.

In testimony whereof, we sign this specification.
